[57] CLAIM

The ornamental design for a combined whistling lollipop and musical slide, as shown.

DESCRIPTION

FIG. 1 is a top front perspective view of a combined whistling lollipop and musical slide, showing my new design;

FIG. 2 is a right side elevational view thereof, the left side being a mirror image thereof;

FIG. 3 is a top plan view thereof;

FIG. 4 is a bottom plan view thereof;

FIG. 5 is a front elevational view thereof; and

FIG. 6 is a rear elevational view thereof.
